US0D1061483S

(12) **United States Design Patent** (10) **Patent No.:** **US D1,061,483 S**
(45) **Date of Patent:** **** Feb. 11, 2025**

(54) **EARPIECE**

(71) Applicant: **OXIWEAR, INC.**, Arlington, VA (US)

(72) Inventors: **Shavini Fernando**, Arlington, VA (US);
George Donald Beckstein, III, Buffalo,
NY (US); **Ben Salthouse**, San
Francisco, CA (US)

(73) Assignee: **OXIWEAR, INC.**, Arlington, VA (US)

(**) Term: **15 Years**

(21) Appl. No.: **29/867,303**

(22) Filed: **Oct. 19, 2022**

(51) LOC (15) Cl. **14-01**

(52) U.S. Cl.

USPC **D14/223**

(57) **CLAIM**

The ornamental design for an earpiece, as shown and described.

DESCRIPTION

FIG. 1 is a front view of a first embodiment of the new design for an earpiece;

FIG. 2 is a rear view thereof, the left side being substantially a mirrored view thereof;

FIG. 3 is a left side view thereof;

FIG. 4 is a right side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is a fifth perspective view thereof;

FIG. 12 is a sixth perspective view thereof;

FIG. 13 is a seventh perspective view thereof; and,

FIG. 14 is an eighth perspective view thereof.
